HAIR CURL PIN

Donald Odell Cross, Evansville, Ind.

Application August 31, 1946, Serial No. 694,373

8 Claims. (Cl. 132—46)

1

This invention relates to a pin or clamp to be employed in holding and fixing curls upon one's head. The invention involves quite a few advantages, particularly in that a structure embodying it holds the curl tightly in a clamped condition, preventing slippage of the pin and assuring a better curling job; it grips the hair under each individual curl to hold the curl flat, and eliminates the possibility of the pin slipping loose from the hair; only one pin is required for each curl; it is very neat appearing and inexpensive in cost of production; and the pins are extremely easy to operate.

These and many other objects and advantages of the invention will become apparent to those versed in the art in the following description thereof as illustrated in the accompanying drawing, in which

Fig. 1 is a top plan view of a structure embodying the invention;

Fig. 2, a view in side elevation;

Fig. 3, a view in front end elevation;

Fig. 4, a view in top plan of a modified form of the invention;

Fig. 5, a view in side elevation of that modified form; and

Fig. 6, a view in rear end elevation of that form.

Referring to the drawing in which like characters of reference indicate like parts throughout the several views, the pin is preferably made out of springy flat wire stock or sheet stock having a thickness on the order of .020 inch. In that form of the invention as illustrated in Figs. 1-3, the pin is formed to have an upturned loop 10 in the nature of a tongue. From the base of this loop 10 there extends a straight length 11 of the material along one side of the center line through the loop, horizontally therefrom, to then curve around outwardly by a bend 12 and thence around and back to form the outwardly, laterally extending loop 13 having the legs 14 and 15 thereon preferably spaced apart, and from the inner end of the leg 15, the material is carried around a bend 16 back into the plane of the length 11 and in alignment therewith, but directed oppositely therefrom by a length 17. From the rear portion of this length 17, the material is twisted through 90 degrees to have the plane thereof vertically disposed in relation to the plane of the lengths 11 and 17. This vertically disposed part of the material is then bent around upwardly and substantially circularly to form a loop 18 from the under and forward portion of which the material is carried by a bend 19 in-

2

wardly and thence forwardly under the loop 10 and to a distance therebeyond by a length designated by the numeral 20.

In the same manner, a length 21 extends rearwardly from the lower portion of the loop 10 by edge contact with the length 11 and in substantially the same plane therewith. From the rear portion of the length 21, the material is carried through a bend 22 outwardly into a substantially straight length 23 and thence around through a loop 24 back inwardly through a length 25 to be finally carried around through a bend 26 into the rearwardly directed straight length 27 which is in edge contact with the length 17. That is, 15 the pin is formed symmetrically on both sides of the longitudinal center line. Then from the rear end of the length 27, the material is twisted through 90 degrees to have it bent upwardly and thence around through the curved loop 28 and 20 back down into a horizontally disposed length 29 to extend outwardly along the length 20. One of these lengths 20 or 29 may be corrugated to leave the other one straight, or both may be corrugated as shown in the drawing. While the 25 clamping portion of the pin extending rearwardly from the loop 10 above the members 20 and 29 is shown to be spaced thereabove, Fig. 2, for the sake of clearness in illustrating the invention, this space will be considerably reduced in 30 practice in order that a clamping action may be obtained between those upper and lower members sufficiently to retain a curl of hair therebetween without undue pressure, the spacing being sufficient to permit easy insertion of the members 20 and 29 spaced apart to pass on each side of the 35 group of hairs forming the curl as it leaves the scalp and to have the curl itself flattened between the upper clamping members and the top edges of the members 20 and 29. That is, the 40 hair is primarily clamped between the members 20 and 29 between the curl and the scalp and then the curl itself is flattened to rest across the top edges of the members 20 and 29 to be flattened 45 thereagainst as well as over the scalp by the upper members including the elements 11-17 and 21-27, inclusive.

The entrance of the members 20 and 29 through the hair or around the hank of hair selected to 50 form the curl is facilitated by pushing the portion 18 relative toward the portion 28 such as by gripping these two members between the thumb and forefinger, which action will spread the forward ends of the members 20 and 29 one from the other. In other words, the natural gripping action of the operator's fingers on the pin

will be to hold the pin by the members 18 and 28 so that the pressure thereon is readily exerted to initially position the pin.

In the form of the invention illustrated in Figs. 4-6, the pin has a central area portion 30 from which diverge forwardly the fingers 31 and 32 in substantially the same plane as that of the zone portion 30. These fingers have their outer ends curved upwardly slightly to facilitate entrance of the curl thereunder. From the rear of the zone 30, the material is bifurcated to merge into the members 18, 19, and 20 on the one side and 28 and 29 on the other side, duplicating the like numbered elements described in the first form. Therefore, the only difference between the two forms resides in the formation of the forward upper clamping members. In any event, it is desired that this top clamping portion of the pin have a lateral effective width sufficient to extend beyond the side faces of the members 20 and 29 appreciable distances in the proportions as indicated in the drawing.

While I have shown and described the invention in the best forms as now known to me, it is obvious that mechanical changes may be employed without departing from the spirit of the invention, and I therefore do not desire to be limited to those precise forms beyond the limitations which may be imposed by the following claims.

I claim:

1. A hair curl pin comprising a pair of hair gripping members normally lying side by side; an upper member extending in part at least laterally across over the said pair of members; and means yieldingly interconnecting said upper member with rear end portions of said pair of members; whereby said pair of members may yieldingly, compressibly straddle a hank of hair adjacent the scalp and said upper member compressibly retain a curl of hair extending from said hank in a flattened condition over said pair of members; said pair of members being normally pressed one toward the other and rear end portions thereof being normally spaced one from the other whereby squeezing together of those rear end portions will rock apart the forward ends of said pair of members; said interconnecting means comprising laterally spaced, substantially arcuate extensions of said pair of members, upper forwardly turned ends of which extensions connect with said upper member.

2. A hair curl pin comprising a pair of hair gripping members normally lying side by side; an upper member extending in part at least laterally across over the said pair of members; and means yieldingly interconnecting said upper member with rear end portions of said pair of members; whereby said pair of members may yieldingly, compressibly straddle a hank of hair adjacent the scalp and said upper member compressibly retain a curl of hair extending from said hank in a flattened condition over said pair of members; said pair of members being normally pressed one toward the other and rear end portions thereof being normally spaced one from the other whereby squeezing together of those rear end portions will rock apart the forward ends of said pair of members; said interconnecting means comprising laterally spaced, substantially arcuate extensions of said pair of members, upper forwardly turned ends of which extensions connect with said upper member; said pair of members having shoulders at said spaced

rear end portions to serve as fulcrums for said rocking apart of the pair of members.

3. A hair curl pin comprising a pair of hair gripping members normally lying side by side; an upper member extending in part at least laterally across over the said pair of members; and means yieldingly interconnecting said upper member with rear end portions of said pair of members; whereby said pair of members may yieldingly, compressibly straddle a hank of hair adjacent the scalp and said upper member compressibly retain a curl of hair extending from said hank in a flattened condition over said pair of members; said upper member comprising a portion extending forwardly of said interconnecting means and therefrom by laterally extending branches.

4. A hair curl pin comprising a pair of hair gripping members normally lying side by side; an upper member extending in part at least laterally across over the said pair of members; and means yieldingly interconnecting said upper member with rear end portions of said pair of members; whereby said pair of members may yieldingly, compressibly straddle a hank of hair adjacent the scalp and said upper member compressibly retain a curl of hair extending from said hank in a flattened condition over said pair of members; said upper member comprising a portion extending forwardly of said interconnecting means and therefrom by laterally extending branches; said branches diverging one from the other forwardly and outwardly from said portion, and having upturned outer ends.

5. A hair curl pin comprising a pair of hair gripping members normally lying side by side; an upper member extending in part at least laterally across over the said pair of members; and means yieldingly interconnecting said upper member with rear end portions of said pair of members; whereby said pair of members may yieldingly, compressibly straddle a hank of hair adjacent the scalp and said upper member compressibly retain a curl of hair extending from said hank in a flattened condition over said pair of members; said upper member comprising a portion extending forwardly of said interconnecting means and therefrom by laterally extending branches; said branches comprising outwardly extending loops, the rear legs of which merge into said portion and the front legs of which return to merge into a forward portion aligned with the first said portion.

6. A hair curl pin made out of flat stock to have a substantially flat central area section, bifurcated forwardly therefrom to have a pair of diverging upper fingers within substantially the same plane as that of the central area, and bifurcated to the rear of that area to form two fingers turned around, downwardly and forwardly thereof to extend forwardly under said area and beyond said upper fingers in central alignment therebetween to be in yielding contact one with the other.

7. A hair curl pin made out of flat stock to have a substantially flat central area section, bifurcated forwardly therefrom to have a pair of diverging upper fingers within substantially the same plane as that of the central area, and bifurcated to the rear of that area to form two fingers turned around, downwardly and forwardly thereof to extend forwardly under said area and beyond said upper fingers in central alignment therebetween to be in yielding contact one with the other; said under fingers being spaced

apart within those portions leaving said central area and those forwardly extending portions, whereby those spaced apart sections may be pressed one toward the other to spread apart the forward ends of those under fingers.

8. A hair curl pin made out of flat stock to have a substantially flat central area section, bifurcated forwardly therefrom to have a pair of diverging upper fingers within substantially the same plane as that of the central area, and bifurcated to the rear of that area to form two fingers turned around, downwardly and forwardly thereof to extend forwardly under said area and beyond said upper fingers in central alignment therebetween to be in yielding contact one with the other; said under fingers being spaced apart within those portions leaving said central area and those forwardly extending portions,

whereby those spaced apart sections may be pressed one toward the other to spread apart the forward ends of those under fingers; said under fingers being turned on edge in respect to said upper fingers and said area, and said portions also being turned on edge to resist bending in the edgewise direction.

DONALD ODELL CROSS.
